FILL INDICATOR

William C. Buttner, Winnetka, Ill., assignor to
The Bastian Blessing Co., Chicago, Ill., a cor-
poration of Illinois

Application July 22, 1941, Serial No. 403,512

18 Claims. (Cl. 62—1)

1

The present invention relates generally to liquefied petroleum gas dispensing systems and more particularly to that portion of the system relating to the filling and measuring of the amount of liquid present in a tank, including certain improvements in the construction, arrangement and machining of fittings.

The present application is an improvement over an earlier filed application Ser. No. 361,682, filed Oct. 18, 1940, now Patent No. 2,400,569, granted May 21, 1946, to Harold L. Norway.

The petroleum product employed in systems with which the present invention is concerned, is preferably of the paraffin series, such as butane or propane, or both, and the storage of this fuel is in the form of a liquefied gas contained preferably in an underground tank where heat present in the ground, as below the frost line, assists in vaporizing the gas for use in a household appliance.

Two ways are employed for vaporizing the gas and regulating its pressure. One way of vaporizing the gas is the so-called "batch" system in which the vaporization is carried on in the storage tank and the vapor is withdrawn as a gas from the tank. The other way of vaporizing liquefied gas is the so-called "flash" system in which the liquefied gas is withdrawn as a liquid from the tank and passed through a pressure reducing regulator which in connection with absorbed heat, causes the liquid to flash into gas.

The present invention may be used with either system and although the two fittings embodying the features of the invention are illustrated in connection with the withdrawal of liquefied gas through a fitting that is generally exposed to atmosphere, it is preferred, as shown in our above mentioned application, to have means for the withdrawal of the gas so disposed as to be insulated from freely circulating atmosphere. The illustration made enables applicant to show how his invention may be employed with a unitary fitting secured in sealed relationship with respect to a single opening in a storage tank, yet having a large assortment of valves and controls for various purposes.

It is one of the objects of the invention to provide an improved filling arrangement for a liquefied petroleum gas system and an improved means for determining when a predetermined safety level is reached in the storage tank during filling operations.

A further object of the invention is to provide an improved unitary fitting which may be secured

2

in sealed relationship with respect to an opening in the tank in one operation.

In view of the fact that an overfilled tank is very dangerous for well known reasons, and devices heretofore provided have relied upon means other than a visual indication such as a vapor return dip tube to prevent overfilling, the present invention is particularly adapted to be of assistance with respect to this latter system to provide a visual indication to enable the operator to shut down filling operations the moment that the predetermined level is reached. In this connection a further object of the invention is to provide a construction wherein a vapor return having a tube that extends to a predetermined maximum fill level in the tank is not relied upon to prevent overfilling but operates as a pressure equalizing means between the replenishing tank and the storage tank, and serves as a fixed filling level indicator.

Approached in another way, an object of the invention is to provide a fixed fill level indicator which utilizes the pressure equalizing conduit as a means to warn when a predetermined filling level is reached in the tank.

A further object of the invention is to provide an improved means for draining the tank of water after it has been tested hydrostatically before being released by the manufacturer for service.

A further object of the invention is to provide an improved unitary fitting or head for liquefied petroleum gas systems and further to provide a slip tube gauge arrangement which will not clog and can be easily manufactured and operated.

These being among the objects of the present invention, other objects will become apparent from the drawings, the description relating thereto and the appended claims.

Referring now to the drawings:

Fig. 1 is a fragmentary vertical section taken through a portion of a unitary fitting mounted upon a riser pipe that is welded to a tank.

Fig. 2 is a section showing the improved construction of the head and the slip tube providing a non-clogging gauge construction.

Fig. 3 is a view similar to Fig. 1 illustrating another embodiment of the invention.

Fig. 4 is an enlarged section of the valved plug shown in Fig. 3.

Fig. 5 is a view similar to Fig. 1 showing another modification of the invention.

In the drawing, a storage tank is indicated at 11 as provided with a standpipe 12 that is mounted by a welded connection 13 where it extends through an opening 14 in the wall of the

tank 11. The standpipe comprises an outer casing 15, an intermediate pipe or pipe vent tube 16, a tubular member 17 of a slip tube assembly 18 and a unitary fitting or head 21. A flange member 19 is employed to provide a cavity in which water will collect when the tank is inverted and an opening 20 through the casing drains water from this cavity to evacuate the tank completely.

The casing 15 supports the head 21 as threaded thereto by tapered threads 22, and the vent or dip tube 16 is suspended from the head by threads 23 in a position preferably concentric to the casing 15. The space between the tube 16 and the casing 15 is as narrow as possible, and the inside diameter of the tube 16 is as large as possible, the relative sizes being determined in relation to the amount of liquid expected to be transmitted between them during a filling operation and the size of a deflector 24 on the tube 16 which size is such that the deflector can be received and withdrawn through the casing 15 as will be described later.

In this way the incoming replenishing liquid is spread out into the form of a thin, cylindrical column of liquid and the interior of the vent tube 16 is large enough in combination with the action of the deflector 24 to prevent entrainment of splashed liquid.

The vent tube 16 extends through the hollow interior 25 of the head 21 to connect with a lateral conduit 26 closed at its outer end by an automatic closing or stem operating vapor return or pressure equalizing valve assembly 27 such as is more particularly described in application Serial No. 397,096 of William C. Buttner and Savin L. Sundstrom, Patent No. 2,405,998, granted August 20, 1946. The space 28 between the casing 15 and the tube 16 opens into a conduit 31 which is closed at its outer end by an automatic closing or stem operated filler valve assembly 32 such as described in the above mentioned application Serial No. 397,096. The valves 32 and 27 open when filling and vent hoses respectively, (not shown) are connected thereto, when the liquid is being introduced into the tank.

Concentricity of the casing 15 and the tube 16 enables the operation of threading the head 21 with different threads to be performed in a single operation, both threads having the same lead.

The vent tube 16 extends down into the tank 11 and serves as a frictional skin carrier for the descending cylindrical column of replenishing fluid. However, for the purpose of providing a quiescent area below the mouth 33 of the tube 16, the conical bell-like deflector 24 is made of a flexible material such as Duprene and is secured to the pipe below the mouth 34 of the casing 15 in a suitable manner, as by a tight fit as shown, or a threaded collar (not shown). In this way, the incoming stream of liquid is fanned out to such an extent that little, if any, surface turbulence is caused in the tank.

In the present invention illustrated, a liquid eduction tube 35 is provided inside the tube 16, close to one wall thereof, to conduct liquefied gas out of the tank through an externally threaded boss 36 adapted to be connected to a service line (not shown) which line includes first and second stage pressure regulators and preferably a vaporizer therebetween. The eduction means is more specifically described in the Savin L. Sundstrom Patent No. 2,303,712 wherein a selector valve 37 and a manual control means 38 are more specifically described. The selector valve enables

the use of the fitting in either batch or flash systems.

The slip tube gauge 18 is an improved one as designed to serve several functions that otherwise would require different parts. The slip tube gauge illustrated functions, as will be described later, in detecting any level in the tank and when lifted to its extreme upper position, functions in cooperation with the vent tube 16 to warn when a maximum fill level has been reached, and also permits the servicing of the packing around the tube.

The slip tube gauge 18 as shown in detail in Fig. 2 comprises a tubular member 17 slidably mounted to slip up and down through the body 41 and sealed with respect to the body 41 by a packing 42 compressed by a gland nut 43. The lower end of the body is machined to provide a valve seat 44 and is externally threaded as at 45 with a tapered thread that is received in the top of the head 21 where it establishes a seal when tightened. The tubular member 17 comprises an upper pipe 46 and a lower pipe 47 both threaded into an intermediate connecting collar 48 which carries on the upper side thereof, a washer 51 engaging the seat 44 when the slip tube is raised to its upper limit. Thus, when the washer 51 is raised against the seat 44, such engagement provides a means whereby the compartment in which the packing 42 is located, is relieved of tank pressures so that the packing 42 can be replaced or repaired whenever desired.

The length of the lower pipe 47 is such that when the washer 51 engages the seat 44 the mouth 52 thereof is drawn up into the vent tube 16, above the intended maximum rated fill level for the tank. In fact, the mouth 52 may be disposed in the tube 16 above the level of the opening 33 so that all levels of liquid in the tank may be gauged by the slip tube when filling operations are terminated. In this way the washer 51 and collar 48 serve not only as a means whereby the packing 42 can be replaced with safety, but also serves as a stop which determines the upper limit of movement of the slip tube gauge.

The upper end of the gland nut 43 is provided with one of the cooperating elements of a bayonet joint 53, and the head 54 that is shown threaded to the upper end of the slip tube member 46 as at 55 is provided with the other element of the bayonet joint 53. In this way, upward creeping of the tube under tank pressure is prevented.

The head 54 has a threaded chamber 56 therein separated from the tube 46 by a partition 57. A hole 58 is drilled through the partition 57 concentrically with respect to the threads in the wall of the chamber and a vent plug assembly 61 carrying a pin 62 surrounded by a washer 63 is threaded into the threaded chamber 56. The plug pins are so constructed and arranged that the pin 62 preferably extends through and beyond the hole 58 at all operative positions so that it serves to provide an annular flow area for fluid through the hole 58 which is very difficult to obstruct by loose particles as compared with a conventionally open small drilled hole. The pin, by extending through the hole, also serves as a means for cleaning the hole.

A laterally extending passageway 65 leads from the chamber 56 near the bottom thereof so that gas or liquid may be discharged therethrough when the slip tube gauge is operated to determine the level of the liquid in the tank.

In testing for the liquid level in the tank with the slip tube gauge, the tube is raised to its upper

limit, the vent plug 61 is loosened until a hissing of escaped gas informs the operator that the gauge is in operation. The tube is then pushed down slowly until liquid discharges from the vent hole 65 at which time a reading is taken from calibrated marks (not shown) on the outer surface of the tube 46, and by these markings, the liquid level in the tank is determined. The vent plug is then tightened and if there is no further use for the tube, the tube is lowered and again locked in place by the bayonet joint.

The vent plug is provided with a T-handle 66 to aid in this manipulation and a protecting cap 67 is threaded to the body 41 to engage a washer 68 which closes the vent hole 71 in the body 41. Thus, when the cap 67 is initially loosened any discharge of fluid from the vent hole 71 serves as a warning that the slip tube gauge has been leaking and the hole 71 vents trapped gas under pressure which otherwise might lift the cap and cause it to strike the operator.

Referring now to that part of the operation of the slip tube gauge which relates to its function as a means for determining when the maximum rated level has been reached during the filling operation, it has been mentioned that the position of the slip tube gauge for this purpose is its upper limit where the mouth 52 of the gauge is disposed upwardly inside the vent tube 16 a spaced distance above the maximum rated level, which, in the particular embodiment illustrated, is represented by the position of the mouth 33 of the vent tube 16 in the tank.

As preliminary to an understanding of this arrangement, it would be well to note at this time some of the physical characteristics of liquefied petroleum gas which have been overlooked in the design of several conventional constructions.

Tanks such as the storage tank 11 are serviced and replenished from a supply tank on a truck. The fluid contents of both of these tanks above the liquid level is a condensable vapor. The pressure existing in each tank in absence of an additional gas such as air, is the vapor pressure of the fluid at the existing temperature, or in other words, that pressure where vaporization and condensation balance each other at the temperature of the liquid in the tank.

Thus, when the supply tank (not shown) is connected to the standpipe by a hose, the pressures in the two tanks tend to equalize except for the hydrostatic head resulting in the difference of the levels of the two bodies of liquid. This head will increase the pressure in the lower tank above the vaporization-condensation balance existing and condensation will tend to take place in the lower tank.

This result is unaffected by presence or absence of a vent tube and takes place whether any vent tube that happens to be provided, extends into the tank a short distance or not.

As conventionally filled and in order to accomplish a rapid filling, the supply tank and ground tank are generally connected so that vapor displaced in the storage tank by incoming liquid will be conducted to the supply tank to replace with vapor the volume of liquid drained therefrom. The vent tube will ultimately become a riser pipe filled with liquid having a hydrostatic head the same as that of the supply hose. From this time on, the unbalanced pressure due to the two hydrostatic or artificial heads will cause vapor trapped in the storage tank to condense until there is no more vapor there and the tank is filled completely with liquid. This action would

be accentuated if the supply tank is warmer than the storage tank.

In conventional systems, either the mouth of the slip tube is relied upon to contact directly the rising liquid level in the tank, in which case splashing causes many false warnings to be made since the size of the slip tube is small enough to entrain liquid in the out-rushing gas, or, the vent tube is separated from the slip tube in which case whichever one has the lower mouth in the tank, functions first before the other completes its intended function.

However, with the present invention, and the arrangement made between the slip tube member and the vent tube, the slip tube gauge will warn the second that the hydrostatic head begins to form, if the mouth of the slip tube gauge is disposed where the hydrostatic column begins to form.

Referring now to Fig. 3 in which like numbers refer to similar parts, the vent return means is illustrated as including a tube 72 threaded as at 73 into the head 21A in communication with the passage 26. At its lower end the tube 72 carries a downwardly opening cup 74 which prevents splashed liquid in the tank being entrained in vapor passing up through the tube 72.

Eduction may be had through the passageway 75, which may be threaded (not shown) to receive a liquid eduction tube. Whenever the liquid eduction tube is absent and the head 21A is employed for batch vaporization, a baffle 76 is mounted between the eduction passageway 75 and the fill passageway 77 which is shown in phantom, so that liquid introduced into the system through the fill opening 32 is deflected downwardly towards the tank by the baffle 76 to prevent entrainment of liquid in the supply of gas going to the service line through the boss 36.

The passageway vent 26 in both embodiments is provided in the heads 21 and 21A by means of a drill and the outer end is plugged as at 78 in the embodiment illustrated in Fig. 1. However, in the embodiment illustrated in Fig. 3 the outer end of the passageway 26 is threaded to receive a plug 81 which has a passageway 82 longitudinally therein receiving a Dill valve 83 seating in the plug body as at 84. The stem 85 of the Dill valve extends outwardly beyond a plug washer 86 into a threaded cavity 87 which cavity has a bleed opening 88 therein adapted to vent any pressure existing in the cavity 87 beyond the seal 86. The seal plug 91 is threaded at both ends to be received in the threading 87 but at one end carries a recess 92 which receives the stem 85 therein, and at the other end carries a stud 93 which may be used to depress the stem 85 to open the Dill valve to permit flow through a restrictor washer 94 preferably having a #54 drill hole 95 therein.

With the plug 81 disposed as described, whenever it becomes desirable to fill the tank the vapor return hose (not shown) is connected to the vapor return assembly 27, the seal plug 91 is removed and turned end for end. The stud 93 is forced against the stem 85 to open the Dill valve. When the liquid level rises to the cup 74 the hydrostatic column immediately begins to form and as soon as liquid is present in the passageway 26, a fog will issue from the vent hole 88 to warn the operator that the tank has reached the maximum filling level. The operator who will be expected to be watching for this indication, will immediately shut down the filling system, disconnect the hoses and return the sealed plug 91 to its original position in which the Dill valve closes and the

stem 85 is protectively received without actuation in the recess 92.

Thus the present invention provides an improved filling device which more accurately assures the correct filling of the tank in a new and improved manner without any increase in the cost of equipment, but rather through the construction and arrangement of the tubes or the utilization of a simple plug device, provides a less expensive construction to manufacture and maintain.

Moreover with the present invention, if the vent pipe fills before a shutoff is had, the hydrostatic head will immediately clear itself after the filling is completed, and the level of the liquid therein will assume the level of the liquid in the tank. Thereafter, as particularly shown in Fig. 1, the slip tube will have sufficient play between its upper limit and the level of the liquid to check accurately the level of the liquid in the tank, even though the tank is overfilled and the level of the liquid is well above the mouth of the vent tube. In fact, the upper level of the slip tube mouth 52 being disposed above the opening 14, it is possible to make an accurate test as to the level of the liquid in the tank especially in those installations where shutoff conditions in the filling operations are difficult to control.

As more particularly shown in Fig. 3 a safety valve 96 and other suitable devices are mounted in or upon the head as more particularly shown in the application Serial No. 361,682 or the features of the invention disclosed herein can be utilized with the fittings disclosed and described in the above referred to application Serial No. 397,096.

Although certain improved embodiments of the present invention have been shown and described herein and ways have also been suggested by which the present invention may be utilized in various dispensing systems, it will be apparent to those skilled in the art that various and further uses, modifications and changes may be made without departing from the spirit or substance of the invention set forth in the objects and the description, the scope of which is commensurate with the appended claims.

What is claimed is:

1. In a liquefied gas dispensing system having a tank, a standpipe comprising a unitary head having coaxial threads thereon, an outer casing secured to the larger thread and to the tank, a pipe secured to another thread and extending into the tank to approximately the fill level thereof, means for filling the tank through the outer casing, means for venting the tank through the pipe, and level measuring means mounted in the pipe to determine the level of liquid present in the tank above the fill level.

2. In a liquefied gas dispensing system having a tank, a standpipe comprising a unitary head having spaced threads thereon, an outer casing secured to the larger thread and to the tank, a pipe secured to another thread and extending into the tank to approximately the fill level thereof, means for filling the tank through the outer casing, means for venting the tank through the pipe, and slip tube level measuring means mounted for movement upwardly in the pipe to a point above the mouth of said pipe to detect the level of liquid which may be present in the pipe above the fill level and including a restricted opening controlled by a valve operable to vent to the atmosphere for visual observation.

3. In combination with a liquefied gas dispens-

ing device having a tank, a standpipe comprising a fitting having a plurality of vertically spaced threads thereon of different sizes, an outer casing secured to the lower thread and to the tank, a pipe secured to another thread and extending into the tank to approximately the fill level thereof, means for filling the tank through the outer casing, means for venting the tank through the pipe including a passageway through the fitting and means including a bleed valve for bleeding to the atmosphere liquid present in said passageway above said fill level when the fill level in the tank has been reached.

4. In combination with a tank for storing liquefied gas under pressure, a standpipe comprising a unitary head having a plurality of fittings thereon including a filling valve assembly, a vent return assembly and a fluid eduction conduit, an outer casing secured to the tank and receiving the head in detachable supported sealed relation, a dip pipe upon said head in communication with the vent return assembly and extending downwardly into the tank to a predetermined level when the head is mounted upon the casing, means for shielding the vent return assembly and fluid eduction conduit from fluid introduced through the filling means and means for detecting the level of liquid in said dip pipe at will.

5. In combination, a tank for storing liquefied petroleum gas, a vent tube extending into the tank to approximately the maximum rated filling level of the tank, a deflector on the tube, a slip tube gauge mounted to slide up and down in said tube comprising a tube, a stop upon the tube for disposing the lower end of the tube above the maximum rated level, and valve means at the top of the tube for educting fluid to determine when the liquid level in the vent tube rises above said maximum level during filling operation including a valve port and a valve member carrying a pin extending through the port when the valve is closed.

6. In combination, a tank for storing liquefied petroleum gas, a vent tube extending into the tank to approximately the maximum rated filling level of the tank, a fitting having an opening surrounded by a valve seat, a slip tube gauge mounted to slide up and down in the opening comprising a tube, a stop upon the tube for disposing the lower end of the tube above the maximum rated level, a seal on top of the stop co-operating with the seat to seal the opening, a removable stuffing box in said opening and valve means at the top of the tube for educting fluid to the atmosphere beyond the opening to determine when the liquid level in the vent tube rises above said maximum level during filling operation.

7. In combination, a tank for storing liquefied petroleum gas, a tube for venting the tank of vapor during filling operations and extending into the tank to approximately the maximum rated filling level of the tank including a flexible deflector on the tube, and means for venting the interior of said tube to atmosphere to detect the presence of liquid in said tube.

8. In combination with a tank for storing liquefied petroleum gas; a fitting adapted to be received in sealed relationship with respect to an opening in said tank; and means for venting the tank of vapor through said fitting during filling operations including a passageway, a dip tube adapted to extend into the tank to a predetermined distance and disposed in communication with said passageway, deflector upon the

bottom of the tube and valve means for venting said passageway to the atmosphere through a predetermined restricted opening.

9. In combination with a tank for storing liquefied petroleum gas; a fitting adapted to be received in sealed relationship with respect to an opening in said tank; and means for venting vapor from the tank through said fitting during filling operations including a passageway, a dip tube adapted to extend into the tank to a predetermined level and located in communication with said passageway, a deflector at the bottom of the tube, and valve means for venting said passageway to the atmosphere through a predetermined restricted opening including a removable plug cooperating with a seal to prevent escape of fluid between filling operations.

10. In a liquefied gas dispensing system having a tank and a casing permanently secured thereto at its lower end, the combination of a unitary head having coaxial threads thereon provided with the same lead, the larger of said threads being received upon the upper end of the casing in threaded pressure sealed relationship, a pipe secured to another thread and extending into the tank through the outer casing to approximately the fill limit thereof, means carried by the head for filling the tank through a space between the pipe and casing, means carried by the head for venting the tank through the pipe, and valve means for ejecting liquid to the atmosphere when the fill level of the liquid in the tank reaches the mouth of said pipe and the liquid level in said pipe rises above said mouth.

11. In combination, a tank for storing liquefied petroleum gas, a vent tube extending into the tank to approximately the maximum rated fill level of the tank for venting a vapor from the tank during filling operations, means for filling the tank with the injection of liquefied petroleum gas in both its liquid and vapor phases along the outer wall of the vent tube including a casing opening into the tank, a deflector disposed on the tube below the opening of the casing in the tank to direct the incoming liquefied gas outwardly away from the tube, and means for venting the interior of said tube to atmosphere to eject liquefied gas in the liquid phase to the atmosphere when the maximum rated filling level in the tank is reached.

12. In combination, a tank for storing liquefied petroleum gas, a vent tube extending into the tank to approximately maximum rated filling level of the tank for venting vapor from the tank during filling operations, a fitting carrying said tube, a casing secured to the tank receiving the tube therethrough and supporting said fitting, a deflector on the tube below the lower end of said casing, said deflector being made of a flexible material and having its maximum dimension greater than the inside dimension of the casing, the flexibility of the material permitting the deflector to be collapsed and inserted into the tank with the tube through the casing while the fitting is being secured in place, and said deflector re-assuming its form when it clears the lower end of the casing.

13. In a gage for liquefied petroleum gas tanks, a housing adapted to carry a slidable tube and provided with an extension therbelow to form a valve seat; a slidable tube disposed through the housing; a stop ring disposed about the tube and spaced from its lower end; a gasket carried on the upper face of the stop ring, the gasket

being arranged to coact with the valve seat to form a valve which will prevent the escape of fluid around the tube when the valve is closed; and a valve normally closing the upper end of the tube and arranged to be opened for the discharge of fluid from the tank and through the tube.

14. In combination with a tank for storing liquefied gas under pressure, a standpipe comprising a unitary head having a plurality of fittings thereon including a filling valve assembly and a vent return assembly, an outer casing secured to the tank and receiving the head in detachable supported sealed relation, a dip pipe upon said head in communication with the vent return assembly and extending downwardly into the tank to a predetermined level when the head is mounted upon the casing, and means for detecting the presence of liquid in said pipe at will including a slip tube gauge the inlet of which is disposed upwardly in the dip pipe above said predetermined level when the slip tube is in its fully raised position.

15. In combination with a storage tank for storing liquefied petroleum gas, a tubular casing extending through a wall of the tank, means for supporting the casing in permanent relation with respect to the tank, an annular depression in the wall of said tank surrounding said casing and drain means including an opening in communication with said annular depression extending through the wall of said casing, said opening being so disposed as to have a portion of its contour outwardly of the inside wall of the tank.

16. In a gage for liquefied petroleum gas tanks, a housing adapted to carry a slidable tube and provided with an extension therbelow; a slidable tube disposed through the housing; a stop ring disposed about the tube and spaced from its lower end; a gasket disposed about said tube intermediate said stop ring and said extension, the gasket being arranged to coact with said extension and said ring to form a seal which will prevent the escape of fluid around the tube when the tube is moved upwardly to the limit of travel; and a valve normally closing the upper end of the tube and arranged to be opened for the discharge of fluid from the tank and through the tube.

17. In a gage for liquefied petroleum gas tanks, a housing having an opening therethrough, a tube slidably mounted in said opening in sealed relationship, a stop member disposed about said tube and spaced from its lower end, a valve device carried by said tube and housing including a valve disc element and a valve seat element, one of said elements being located on said stop member and the other of said elements being disposed around said opening in said housing on the side thereof facing said stop member, said stop member and said housing closing said valve device when the tube is moved upwardly the full limit of travel, and a second valve device normally closing the upper end of said tube and arranged to be opened for the discharge of fluid from the tank.

18. In a gage for liquefied petroleum gas tanks, a housing adapted to carry a slidable tube, a slidable tube disposed in said housing, packing removably received in said housing and forming a seal between the wall of said tube and said housing, a stop ring disposed about said tube at a point spaced from its lower end, a valve seat element and a valve disc element, one of said

elements being disposed on the inner end of said housing and the other on the side of said stop ring facing said housing, said elements co-acting to form a seal when said tube is moved upwardly the limit of travel, preventing leakage in the event said packing is removed.
